UNITED STATES PATENT OFFICE.

ROBERT T. PARISEN, OF KNOXVILLE, PENNSYLVANIA, ASSIGNOR TO LAWSON MANUFACTURING COMPANY, OF HOMESTEAD, PENNSYLVANIA, A CORPORATION OF PENNSYLVANIA.

THERMOSTATIC VALVE.

1,075,934.

Specification of Letters Patent. Patented Oct. 14, 1913.

Application filed December 13, 1912. Serial No. 736,560.

To all whom it may concern:

Be it known that I, ROBERT T. PARISEN, a citizen of the United States, and a resident of Knoxville, in the county of Allegheny and State of Pennsylvania, have invented certain new and useful Improvements in Thermostatic Valves, of which the following is a specification.

One object of this invention is to provide improved means for transmitting the movement of the thermostatic device to effect the opening and closing of the valve, with improved means for adjusting the valve movements to different predetermined temperatures.

A further object is to provide for quickly or suddenly seating and unseating the valve when the requisite temperature has been attained, the operation distinguishing in this regard from those operations heretofore proposed which are characterized by sluggish movements accompanied by uncertainty as to when and to what extent the valve will open and without certainty as to its complete closing.

Another object is to provide improved means, accessible at the exterior of the valve, for adjusting the mechanism which transmits the movement of the thermostatic device to the valve.

In the accompanying drawings, Figure 1 is an elevation of a valve device constructed in accordance with the invention, and Fig. 2 is a longitudinal section on line 2—2 of Fig. 1. Fig. 3 is a sectional elevation on line 3—3 of Fig. 2. Fig. 4 is a cross section on line 4—4 of Fig. 2. Fig. 5 is a longitudinal section on line 5—5 of Fig. 4. Figs. 6 and 7 are details of the adjustable lever carrier.

Referring to the drawings, 2 designates the valve body provided with gas inlet 3 and outlet 4. Within the body is seat 5 for check valve 6 which is held normally seated by spring 7, also by pressure of gas admitted at 3, the spring and valve being confined by cap 8.

The side of the valve body opposite cap 8 is formed with the tubular or hollow extension 9 having threaded extremity 10 adapted to be secured in the wall of a stand boiler or other water container, not shown. Projecting from extension 9 into such boiler is the thermostatic tube 11 formed preferably of copper. Within the tube and secured to the

outer end of the latter is rod 12 formed of steel or other material having a different coefficient of expansion from the tube, the inner end of the rod extending into the valve body and adapted to operate the valve in 60 manner presently to be explained.

Located within body 2 is carrier 13 having a tubular extension 14 which is movable in and guided by body extension 9. Fulcrumed in carrier 13 are the co-operating levers 15 and 16, hereinafter referred to as the "first" and "second" levers, respectively, lever 15 being disposed transversely of the thermostatic rod 12 with the inner extremity of the latter engaging said lever 70 near its fulcrum 15'. Lever 16 is disposed reversely to and preferably substantially parallel with lever 15, and is formed with an edge-like projection 17 near its fulcrum 16' which is engaged by the free portion of 75 lever 15. The free portion of lever 16 extends across the center of valve 6 and is adapted to engage valve stem 6'.

Carrier 13 is formed with threaded socket 18 and adjustable therein is the threaded 80 inner extremity 19 of stem 20, the latter rotatably confined in a wall of body 2 by gland 21. Stem extremity 20' is adapted to receive a wrench or other turning device. Secured to stem 20 at the exterior of the 85 valve body is pointer arm 22 which is curved to place its extremity over a temperature scale 23 that may be conveniently located on the exterior of body 2.

The adjustment is preferably such that 90 normally, i. e., when the water in the boiler is being maintained at a desired temperature, there is slight clearance or slack between lever 16 and valve stem 6', as in Fig. 2. The contraction of tube 11 resulting 95 from lowering the temperature of the water, as when hot water is drawn off and replaced by cold water in the boiler, forces rod 12 outwardly and moves the co-operating levers in direction to unseat the valve and 100 permit gas to pass therethrough to the burner.

It is characteristic of the invention that the valve opening movement and the pressure of rod 12 must overcome slight elasticity inherent in the levers, and must overcome the inertia of the valve plus the gas pressure and spring pressure behind the valve before the latter will open. But when these opposing conditions are overcome the 110

valve opens suddenly and positively, its movement doubtless being accelerated by the appreciable recoil or rebound of the levers. Substantially a like performance ensues when the valve closes, the closing movement being opposed until the opposing pressure suddenly yields and the valve closes with a snap. In the opening and closing movements edge 17 of lever 16 slides on lever 15, as will be understood. It is further characteristic of the invention that the operating parts are contained within the valve and fully sensitive to every tendency to move. In this respect the mechanism is superior to those of prior design wherein one or more parts extend to the exterior of the valve with the friction of stuffing boxes, etc., tending to obstruct their movement and hence decreasing their sensitiveness.

20 The lever carrier 13 is moved toward and from the valve by stem 22, and with the parts properly proportioned and adjusted it is necessary to turn the stem very slightly to vary the temperature at which the valve will open, and this may be determined with accuracy by adjusting stem 22 to the graduations 23. To cause the valve to open at a higher temperature, stem 20 is turned to the right, thereby moving carrier 13 toward rod 12, thus swinging lever 15 toward the valve, and similarly moving lever 16, with the result that the rod and valve are more closely or directly connected, and correspondingly decreasing the contraction of the thermostat and the movement of the levers necessary to open the valve. A reverse movement of stem 20 adjusts the carrier toward the valve, thereby increasing the necessary throw of the valve operating mechanism, and necessitating greater cooling of the thermostat with corresponding decrease in temperature of the water before the valve is operated. From the foregoing it will be seen that the movement of carrier 13 in either direction is so compounded by the levers that only very slight movement of the carrier is required to materially affect the operation of the valve.

I claim:-

- 50 1. The combination of a valve body provided with a valve seat, a valve, a thermostatic device, a support movable within the valve body, a stem rotatably mounted in the wall of the body and at its inner end having threaded connection with the support for adjusting the latter relatively to said device and valve, and means carried by the support for connecting the thermostatic device and the valve.
- 60 2. The combination of a valve body provided with a valve seat, a normally closed valve, the body having a hollow extension opposite the seating face of the valve, a thermostatic device connected to the valve body and movable within the hollow extension, a

carrier within the valve body with a portion of the carrier movable in and guided by the body extension, means for adjusting the carrier, and means mounted on the carrier for operatively connecting the thermostat 70 and valve.

3. The combination of a valve body provided with a valve seat, a valve, the body provided with a hollow extension, a thermostatic device connected to the valve body 75 and movable within the extension, a carrier movable within the body and having a part within and guided by the body extension, co-operating levers mounted on the carrier with one lever adapted to engage 80 the thermostatic device and another lever adapted to engage the valve, the carrier provided with a threaded socket, and a stem rotatable in a wall of the body and adapted to be rotated at the exterior of the latter, 85 the inner portion of the stem being threaded and adapted to engage the threaded socket of the carrier.

4. The combination of a valve body provided with a valve seat, a valve, a thermostatic device, an immovably held carrier, 90 means for adjusting the carrier in the plane of movement of the thermostatic device, and means movably mounted on the carrier and adapted to multiply the adjustment movement of the carrier with said means adapted to connect the thermostat and valve.

5. The combination of a valve body provided with a valve seat, a valve, a thermostatic device, a carrier movable within the body independently of the thermostat, means on the carrier for connecting the thermostatic device and valve, and a stem extending through and having a fixed bearing in a wall of the valve body with the stem having threaded connection with the carrier.

6. The combination of a valve body provided with a valve seat, a valve, the body formed with a hollow extension, a thermostatic device connected to the valve body 110 and movable within said extension, a hollow support slidable in the body extension with the thermostatic device extending into the support, means for slidably adjusting said support, and means carried by the support for transmitting movement from the thermostatic device to the valve.

7. The combination of a valve casing having a hollow guide-forming portion, a valve, a carrier fitting and adjustable in the guide-forming portion of the casing, adjusting means for immovably holding the carrier in adjusted position, a thermostat, and means mounted on the carrier for operatively connecting the thermostat and valve.

8. The combination of a valve body provided with a valve seat, a valve, a thermostatic device spaced from and movable in the same direction as the valve, a lever carrier, means for positively moving the car- 130

rier in reverse directions in the plane of movement of the thermostat and for holding the carrier fixed in adjusted position, and reversely extending levers 15 and 16 ful-

5 crumed to the carrier in overlapping relation intermediate the thermostat and valve with the thermostat adapted to engage lever 15 near its fulcrum and with lever 15 adapted to engage lever 16 near the fulcrum of the latter, the free portion of lever 16

10 adapted to engage the valve.

9. The combination of a valve body provided with a valve seat, a spring-closed valve, a thermostat movable in the same direction as the valve and spaced from the

15 seating face of the latter, a lever carrier,

two reversely extending levers interposed between the thermostat and valve and fulcrumed to the carrier in overlapping relation with one lever adapted to be engaged by the thermostat and with the free portion of said lever adapted to engage the other lever and with the free portion of the said other lever adapted to engage the valve, and means for adjusting the lever carrier.
